(57) **CLAIM**

The ornamental design for a cell phone pocket, as shown and described.

DESCRIPTION

FIG. 1 is a perspective view of my cell phone pocket mounted on a transformer plugged into a wall outlet, the cell phone, the cell phone transformer and wall outlet being shown in broken lines;

FIG. 2 is a perspective view similar to FIG. 1 but without the broken line showing of the cell phone, the cell phone transformer and wall outlet;

FIG. 3 is a front view of my cell phone pocket;

FIG. 4 is a rear view of my cell phone pocket;

FIG. 5 is a right side view of my cell phone pocket, the left side being a mirror image thereof;

FIG. 6 is a bottom plan view of my cell phone pocket; and, FIG. 7 is a top plan view of my cell phone pocket.

The broken lines are for illustrative purposes only and form no part of the claimed design.
